(57) **CLAIM**

The ornamental design for a television receiver, as shown and described.

DESCRIPTION

1. Television receiver

1.1 : Perspective

1.2 : Front

1.3 : Back

1.4 : Left

1.5 : Right

1.6 : Top

1.7 : Bottom

1.8 : Perspective

1.9 : Enlarged

1.10 : Exploded

The present design is a television receiver in which a partial configuration can be customized according to user needs; the present design is characterized in that a system box on the rear surface of a panel is configured vertically since a film-type speaker is applied rather than an additional speaker module, thereby ensuring a neat wide rear surface and a slim panel; fig. 1.8 is a bottom perspective view; fig. 1.9 is a partially enlarged view of fig. 1.8; fig. 1.10 is an exploded perspective view of the present design, showing a set-top (Continued)

box or a USB and the like can be stored in a storage space at the upper end of the rear surface of the panel.
